CHARLES V. HAYNES, OF ARDMORE, PENNSYLVANIA, ASSIGNOR TO HOFFMAN SPECIALTY COMPANY, OF WATERBURY, CONNECTICUT, A CORPORATION OF ILLINOIS.

STEAM-IMPELLED MOTIVE APPARATUS.

Application filed June 17, 1925. Serial No. 37,603.

The present invention relates to motive apparatus or devices which are designed to be impelled by steam pressure at more or less irregular intervals to effect a change in the relation of certain movable parts in consequence of a change in the controlling steam pressure. Well-known examples of such apparatus are the familiar damper regulators for steam boilers, of which the steam impelled motive member is usually a flexible rubber or metallic diaphragm extending across the bottom of a closed chamber and held in leakage-tight contact with the walls of the chamber. The embodiment of the present invention which I have illustrated in this specification has been designed more especially for use as a damper regulator, wherefore in the following detail description I shall generally refer to the apparatus as a damper regulator, but without implying thereby any restriction in the protection which I claim, beyond that set forth in the claims as construed with respect to the prior art. Furthermore, the movable steam actuated part of the regulator herein shown is a rubber or metallic diaphragm; but I include within the scope of the invention which I claim, all equivalents for such a diaphragm.

The object of the invention is to overcome the sluggishness of regulators and equivalent apparatus of the sort above referred to. Such sluggishness is due to the fact that water of condensation collects in the pressure chamber, and rests on the movable diaphragm; and that the volume and weight of the water thus collecting may vary, being greater when the diaphragm is depressed than when the diaphragm is raised. The effect of this condition with the regulators heretofore used is that, if the regulator is moved when the steam pressure reaches a certain intensity, the subsequent accretions of water to the quantity resting on the diaphragm increase the resistance to the counter force which tends to return the diaphragm, so that the previous condition of the regulating apparatus will not be restored until the steam pressure has dropped to a point lower than the pressure which caused the initial displacement of the diaphragm. This condition has been a serious drawback in connection with pressure operated damper regulators for steam boilers, since it has made impossible the automatic

maintenance of a substantially uniform steam pressure. This drawback is especially serious with heating systems of the so-called vapor heating class, which are designed to operate with a working pressure of only a few ounces, because the pressure due to the accumulation of water in the circumstances above described bears a relatively large ratio to the pressure which it is desired to maintain in the boiler.

For reasons well understood in the art, it is necessary or desirable in steam operated regulators of the sort with which this invention is concerned, to locate the diaphragm below the only connection or connections through which water of condensation can drain out of the pressure chamber, whereby a body of water resting on the diaphragm is always maintained and an unavoidable continuing accumulation of water, due to condensation of steam, takes place in the chamber after depression of the diaphragm. The problem which I have solved by this invention has been to limit and control the accretions of water supported by the diaphragm, while at the same time retaining the desired presence of water over the diaphragm. My invention by which I have solved this problem and accomplished the object above stated, comprises the use of a displacer in connection with an internal pressure actuated member, in a closed steam chamber, arranged and acting to displace from the chamber, or prevent accumulations therein, a volume of water bearing a desired ratio to the displacement volume of the pressure actuated member, and permissibly equal to, or less than, or greater than, the displacement volume of said pressure actuated member.

I will now describe the specific embodiment of the invention herein disclosed with reference to the drawings.

In the drawings:

Figure 1 represents so much of a damper regulator for steam boilers as is necessary for explanation; showing the pressure chamber in cross section and the movable parts in the position taken when the steam pressure is below the point at which it operates the apparatus;

Fig. 2 is a similar view showing the condition of the apparatus after displacement by steam pressure;

Fig. 3 is a perspective view of the water

displacer shown in the preceding figures.

Like reference characters designate the same parts wherever they occur in all the figures.

5 The numeral 10 represents a suitable casing enclosing a chamber, across the lower part of which a flexible diaphragm 11 is placed. The diaphragm may be made wholly or partly of vulcanized rubber composition, or of any other material or structure suitable for the purpose. It is secured at its periphery to the casing by a bottom head or wall 12, being gripped between flanges 13 and 14 on the casing and head respectively, which flanges are fastened together by bolts 15. A perforated rigid plate 16 is mounted over the diaphragm, substantially as shown, to protect the diaphragm. A head 17, having a substantial area, bears 10 on the under side of the diaphragm and is formed with a stem 18 projecting through the casing head or wall 12 and bearing on an arm 19 pivoted at 20 to a plate or holder 21 which is secured to the wall 12 in a manner permitting an angular adjustment about the axis of the chamber. There is secured to the arm 19, in a manner permitting it to be adjusted endwise, a bar 22 on which is mounted a weight 23 which is adjustable 15 lengthwise of the bar. The bar is provided to transmit motion from the diaphragm to the dampers or other draft controlling means of a steam boiler, and typifies any means which may be operated or controlled 20 by movements on the diaphragm. The weight 23 typifies means for applying a counter force to the diaphragm in opposition to the steam pressure, and also typifies means for regulating or determining the 25 steam pressure which will cause the diaphragm to be displaced.

As thus far described, the apparatus is substantially like damper regulators heretofore used, and may be understood as connected in any usual way with regulating dampers or valves.

From the side of the casing 10 there extends a boss 24 to receive a pipe leading from the boiler or other source of steam pressure, 50 such boss and pipe being large enough to conduct steam to the regulator without sensible drop in pressure. The steam entrance to the chamber, however, is through a gateway 25 at the desired height above the uppermost position of the diaphragm. This gateway is also the drainage outlet for return of water of condensation to the boiler connection. The piping between the regulator and the boiler is, in part at least, lower 55 than the bottom of the gateway 25 at all points in the length of such piping, whereby said gateway establishes the maximum height to which water may rise in the pressure chamber.

60 When the apparatus is in operation it is

in open connection with the boiler, and the condensation of steam in the chamber maintains a body of water above the diaphragm up to the level thus limited.

It will be readily apparent by comparison of Figures 1 and 2 that when the diaphragm is displaced downward, it substantially enlarges the volume of the chamber below the level of the gate 25. Such enlargement I will call the "displacement volume" of the diaphragm. When the diaphragms of regulators as heretofore used remain displaced in the manner illustrated in Figure 2, for any considerable length of time, continuing steam condensation adds to the water body, 75 and if the condition exists long enough, the accumulating water may rise to the level of the gate, thus adding to the water on the diaphragm a further quantity equal to the total displacement volume of the diaphragm. The weight of this additional volume of water must be lifted by the counter force of the weight 23 in again raising the diaphragm after the boiler pressure has subsided; and it 80 delays the raising of the diaphragm until the boiler pressure has subsided by an amount equal to the weight (per unit of area of the diaphragm) of the additional water.

The means by which I prevent such increase of weight on the diaphragm, 85 comprises a displacer 26 which, as shown here, is provided with or connected to a central stem 27 resting on the diaphragm and guided below by a central hole in the plate 16, and guided above the displacer by a guideway 28 in the top wall of the casing. The displacer is thus caused to descend and rise by and with the diaphragm and to the same extent. In the present illustration the displacer is a disk made as a metal casting 100 having an impervious bottom and a rising peripheral lip 29, and its dimensions are of such value that its geometrical or space volume, by which I mean the volume included between the lower side of its bottom, the outer surface of said lip, and the plane in 105 which the upper edge of said lip lies, bears the desired ratio to the displacement volume of the diaphragm; being preferably substantially equal to such displacement volume, although it may be greater or less in any desired measure. In the preferred construction the solid material of the displacer is made relatively thin, in order that its 110 weight may not be excessive, and in the space surrounded by the lip 29 are ribs which stiffen the structure and leave pockets in which water may collect by condensation or by overflow when the displacer is lowered. Under the conditions of use the displacer is 115 a member having a constant volume and weight.

The displacer is so related to the diaphragm that, when the diaphragm is fully raised, the bottom of the displacer is at the 120

level of the bottom of the gateway 25, that is, at the maximum height to which water may be contained in the chamber. Then as the diaphragm descends, the displacer occupies part of the space below such maximum water level, reducing the volume of such space in its upper part at the same time that the space is enlarged at the lower part, and in substantially equal measure.

10 It is to be understood that the weight 23 will be adjusted to counter balance the weight of the diaphragm, displacer and accumulated water, plus any steam pressure lower than that at which the apparatus is 15 designed to operate. After displacement of the diaphragm, by steam pressure above the predetermined degree, the dead weight of diaphragm, displacer and water supported by the diaphragm remain substantially the same as before; that is, when the displacer volume is substantially equal to the displacement volume of the diaphragm, and there is no opportunity for more water to collect and increase the dead weight on 25 the diaphragm. Thus the regulator is equally sensitive in responding to a decreasing pressure condition, after having been displaced, as to an increasing pressure condition.

30 In order to make the displacer somewhat heavier than the water which it displaces, but not much heavier, I have constructed it as a shell of material heavier than water and suitably formed to hold water, but with 35 its structural material comprising only a relatively small part of its total space or displacement volume; at the same time making it rigid enough to meet the conditions of use. Equality or excess of 40 weight in the displacer, as compared with the weight of the displaced or excluded water, has the practical utility of causing the displacer to descend with the diaphragm by gravity and avoiding need of any draft connection with the diaphragm. It will be noted that ample space for passage of steam is left between the periphery of the displacer and the walls of the chamber, whereby the steam pressure acts 45 equally on both sides of the displacer.

50 The same invention, operating according to the principles above described, may be also applied to the purpose of causing a gradual closing of the dampers with an increasing steam pressure, and a gradual opening of the dampers again; or of causing a partial rather than a complete closing of the dampers when the pressure reaches a certain height. This effect may 55 be produced by making the displacer with a larger volume than the displacement volume of the diaphragm, and so shaping the displacer that, as it descends, it forces some of the water out of the chamber and

thus reduces the dead weight on the diaphragm, causing the diaphragm to be arrested before reaching the end of its possible range of movement. On the other hand, by making the displacer of less volume than the displacement volume of the diaphragm, the diaphragm may be caused to remain in its fully displaced position until a certain predetermined decrease of pressure has occurred, before being again raised by the counter force.

75 What I claim and desire to secure by Letters Patent is:

1. A steam impelled device of the character described, comprising a closed pressure chamber having a steam connection, 80 a downwardly movable member closing said chamber below said steam connection, yieldable means constantly tending to move said member upward, and a displacer movable across the level of said steam connection in unison with movements of the afore-said movable member.

2. A steam impelled motive apparatus comprising a steam chamber having at its bottom a movable diaphragm and having a lateral opening arranged to establish a maximum level to which water accumulates on the diaphragm may rise, and a displacer movable upward and downward in unison with the diaphragm and arranged to occupy an increasingly large part of the water containable space in the chamber in consequence of its downward movement.

3. A steam impelled motive apparatus comprising a steam chamber having at its bottom a downwardly and upwardly movable diaphragm, said chamber having an opening at a level above the diaphragm through which accumulated water of condensation may escape, and by which the upper limit of the water containing space in the chamber is established, means arranged to exert on the diaphragm an upward force counter to the steam pressure, and a displacer in the chamber arranged and operating to move, in unison with the diaphragm, across the said upper limit.

4. A steam impelled motive apparatus comprising a steam chamber having at its bottom a downwardly and upwardly movable diaphragm, said chamber having an opening at a level above the diaphragm through which accumulated water of condensation may escape, and by which the upper limit of the water containing space in the chamber is established, means arranged to exert on the diaphragm an upward force counter to the steam pressure, and a displacer in the chamber arranged and operating to move, in unison with the diaphragm, across the said upper limit, the volume of that part of the displacer which so moves across said upper limit bearing

4. a predetermined relation to the displacement volume of the diaphragm.

5. A steam impelled motive apparatus comprising a steam chamber having at its bottom a downwardly and upwardly movable diaphragm, said chamber having an opening at a level above the diaphragm through which accumulated water of condensation may escape, and by which the upper limit of the water containing space in the chamber is established, means arranged to exert on the diaphragm an upward force counter to the steam pressure, and a displacer in the chamber arranged and operating to move, in unison with the diaphragm, across the said upper limit, that portion of said displacer which so moves across said upper limit being sub-

stantially equal in volume to the displacement volume of the diaphragm.

20

6. The combination with a steam chamber having a diaphragm at its bottom of a displacer movable in unison with said diaphragm and disposed to limit accumulation of water of condensation on said diaphragm.

25

7. The combination with a diaphragm in a steam impelled motive apparatus, of a displacer comprising a shell of solid material having provisions for holding water, the volume of said displacer, including the water content thereof, being substantially equal to the displacement volume of the diaphragm.

30

In testimony whereof I have affixed my signature.

CHARLES V. HAYNES.
